UNITED STATES PATENT OFFICE.

NICHOLAS RAPPLEYEA, OF ROCHESTER, NEW YORK, ASSIGNOR TO THE STEIN MANUFACTURING COMPANY, OF SAME PLACE.

DESIGN FOR A BURIAL-CASKET.

SPECIFICATION forming part of Design No. 17,784, dated October 11, 1887.

Application filed May 28, 1887. Serial No. 239,704. Term of patent 14 years.

To all whom it may concern:

Be it known that I, NICHOLAS RAPPLEYEA, of Rochester, in the county of Monroe, in the State of New York, have invented a new and original Design for Burial-Caskets, of which the following, taken in connection with the accompanying drawings, is a full, clear, and exact description.

My invention relates to a new and original design for burial-caskets; and it consists, essentially, in the design for the ornamental border-molding herein described and claimed.

In specifying my design reference is had to the accompanying drawings, forming a part of this specification, like letters indicating corresponding parts in both the views.

Figure 1 is a top plan view of my new design, showing the same applied to a burial-casket lid or top; and Fig. 2 is a transverse sectional view taken on line *x x*, Fig. 1, and showing the contour in cross-section of the ornamental moldings, these two views being deemed essential to fully illustrate my design.

The leading feature of my design consists, essentially, in a burial-casket lid having a concave raised molding combined with a plain or curvilinear base-molding, whereby the casket-lid rises in easy and graceful lines from the marginal edges toward the center of the lid, which is provided with panels extending longitudinally of the casket, the effect being a graceful combination of curved surfaces, the curves of which rise in easy lines from the outer edge of the lid gradually toward the center and culminate in the concave top molding surrounding the central panel of the lid, it being understood that the lid is laid off into sections corresponding to the head-section, central section, and foot-section of the casket, and that the design is applied to the lid as shown.

A denotes the casket lid or top, which may be of any desirable form or material.

a is the gracefully rounded or curvilinear marginal edge of the lid, rising gradually from the extreme edge to the molding *b*, which is mounted on top of the margin of the lid *A*, as shown in Figs. 1 and 2.

The molding *b* rises to the offset curve *c*, as best shown in Fig. 2, and culminates with the

concave-shaped molding *d*, which is hollow, as best shown in the sectional view, Fig. 2, and serves as a marginal molding surrounding the central portion, *f*. The central portion, *f*, may be curved, as shown in Fig. 2, or may be flat, as desired, since the effect of the design is not changed by the contour of the central panel in cross-section.

It will be observed that, as illustrated in Fig. 1, the ends of the casket-lid *B* are rounded gracefully, and the ends of the molding *b c d* coincide with the contour of the ends of the casket. The central section, *C*, of the lid is composed of moldings combined in the same manner as those shown in the end sections of the lid, and the central panel thereof extends transversely across the lid instead of lengthwise, as in the end section.

It will be observed that as applied to a casket-lid the ornamental molding *d*, with the beads or curves *b c e*, serve to set off the lid in the central portion, *f*, and with the surrounding lines of raised work fall gracefully toward the curvilinear plain surface *a*, which terminates at the outer edges of the lid *A*.

Having thus fully described my design, what I claim as new, and desire to secure by Letters Patent, is—

1. A design for burial-caskets, consisting of the curvilinear broad margin *a*, rising from the edge of the casket-lid to the molding *b*, and the molding *b*, rising to and culminating in the concaved top molding *d*, substantially as herein described.

2. The design for a burial-casket herein shown and described, consisting of the panel *f*, surrounded by the raised molding *e*, having a concave-shaped top, *d*, and having its marginal lines parallel and falling gradually to the base of the marginal molding at the outer edges of the casket-lid.

In testimony whereof I have hereunto signed my name, in the presence of two attesting witnesses, at Rochester, in the county of Monroe, in the State of New York, this 25th day of May, 1887.

NICHOLAS RAPPLEYEA.

Witnesses:

FRANK M. ELLERY,
GEO. P. HESS.
